(57) CLAIM

We claim the ornamental design pattern for sole plate of a golf club head, as shown and described.

DESCRIPTION

FIG. 1 is a perspective view of the sole plate of a golf club head; and,

FIG. 2 is a plan view thereof.

The ornamental design that is claimed is shown in solid lines in the drawings. The broken (dashed) lines shown in FIGS. 1 through 2 are included for the purpose of illustrating environmental elements only and form no part of the claimed design.
